UNITED STATES PATENT OFFICE

2,569,515

DAMPER FOR CLOTHES DRIERS

Donley S. Collins, Milwaukee, Wis., assignor to
 A. O. Smith Corporation, Milwaukee, Wis., a
 corporation of New York

Application August 10, 1946, Serial No. 689,763

7 Claims. (CL. 34—54)

1

This invention relates to a damper for clothes driers.

In drying clothes in a clothes drier by circulating hot air, in order to conserve on electricity or gas in the initial heating of the clothes and also to accomplish the drying operation in minimum time, it is desirable to accelerate the heating of the moist clothes to a temperature at which the moisture is driven off rapidly. It has been found that this may be accomplished by restricting the flow of hot air through the drum until certain temperatures are obtained such as 160° F. before permitting unrestricted flow of air through the drum. However, when the clothes are heated quickly a considerable amount of moisture is given off and the outlet pipe becomes full of water which results in injury to the pipe and the problem of having the water flow back into the unit rather than being discharged.

The principal object of the invention is to provide a damper unit that permits quick heating of the clothes and at the same eliminates collection of moisture in the outlet pipe.

Another object of the invention is to provide a damper in a clothes drier which is operated by the temperatures present in the unit.

A further object is to provide a damper in a clothes drier which permits air to flow through the outlet pipe without flowing through the drum of the drier.

Another object is to restrict the flow of air through the drier drum without restricting the flow of air through the discharge pipe or stack.

A further object is to dilute the air which comes from the drying chamber before it enters the blower to reduce the moisture content in the final exhaust from the drier.

Another object is to provide for drawing cool air into the spaces between the drying chamber and the outer panels to maintain both the panels and the controls of the drier substantially cool at all times.

These and other objects of the invention will appear hereinafter in connection with the following description of several embodiments of the invention illustrated in the accompanying drawings.

In the drawings:

Figure 1 is a front elevation view of a clothes drier with parts broken away and sectioned;

2

Fig. 2 is a view of the drier from the right side with the side panel removed and with parts in elevation and section;

Fig. 3 is a top sectional view of Figure 1;

Fig. 4 is an enlarged fragmentary section of the damper assembly with the damper open; and

Fig. 5 is a view similar to Fig. 3 with the damper closed.

10 The clothes drier illustrated in the drawings as an example of a drier to which the invention may be applied, is similar to that described and claimed in the application of Adolph Pokras, entitled, Clothes Drier, Serial No. 626,788, filed November 5, 1945, now Patent No. 2,477,820, and granted August 2, 1949, assigned and to the assignee of the present invention.

The housing of the drier comprises the generally square casing 1 formed of front, rear and side panels assembled with a base 2 and closed at the top by the removable cover 3. A small door 4 in the front panel of the casing permits access to the inside.

20 The clothes carrying drum 5 is disposed for rotation within the casing and comprises a cylindrical perforated metal member which is closed at the ends by the front plate 6 and the rear plate 7.

A short horizontal shaft 8 has one end suitably secured to the center of rear plate 7 of the drum and the other end is mounted for rotation within bearing 9 suitably disposed within the rear end plate 10 which is secured to base 2 and supports drum 5 for rotation through short shaft 8.

30 The motor 11 is mounted on brackets 12 at the lower right hand rear corner of the drier. The motor 11 by its shaft 13 drives drum 5 through a speed reducing unit and drive roll 14 preferably in a clockwise direction.

40 Motor shaft 13 extends through motor 11 and the front end of the shaft is directly connected to the rotor of the rotary blower unit 15 which is connected to the rear side of the wind box 16 or inlet conduit at the lower right hand front corner of the drier.

45 The outlet or exhaust pipe 17 extends upwardly from blower unit 15 and then rearwardly and out through the rear of the drier to discharge the air circulated through the unit.

The drum 5 is surrounded by the inner baffle 18, and inner baffle 18 is partially surrounded on the left side, looking from the front in Figure 1, by the outer baffle 19. Baffle 19 is radially spaced from baffle 18 to provide a chamber therebetween and is secured to the latter near the uppermost portion thereof. The baffles are suitably secured to base 2 and extend the length of the unit from the rear end plate 10 to the front end plate 20. The front plate is secured to the base 2 and extends vertically between the drum and the front panel of the casing.

The drier is shown as supplied with heat by a gas burner unit 21 which is secured to base 2 between baffles 18 and 19 at the left side of the drier.

Air drawn into the unit by blower 15 enters through openings 22 in base 2 at the left side of the unit and through the openings 23 at the right side of the drier. The air entering through openings 23 passes over the top of the inner baffles 18 and 19 inside casing 1 and downwardly to enter the burner chamber through openings 23' in baffle 19, adjacent burner unit 21. The air entering the burner chamber through openings 22 and 23' is heated by burner unit 21 in the gas chamber between baffles 18 and 19 and then flows upwardly and enters the drum 5 through opening 24 in the upper portion of inner baffle 18. The line of joinder of baffle 19 to baffle 18 previously described is at the uppermost side of opening 24 so that the air is forced to enter the drum through the opening 24.

If an electric heating unit is employed for heating the air the construction shown and described in the application previously referred to may be employed.

After circulating through drum 5, the air flows downwardly through the lint catcher 25 and into the longitudinal passage 26 between the legs of baffle 18.

The air then flows from passage 26 through wind box 16 and is driven into the outlet pipe 17 by the blower 15.

Referring now more particularly to the invention the damper 27 is hinged to one side of wind box 16 by pivots 28 to open and close the opening 29 in the wind box.

Pivots 28 are located slightly removed from the top of opening 29 and the damper fits the opening so that the upper portion of the damper is free to swing inwardly when the damper opens.

The link or rod 30 is pivoted to the inside of damper 27 at a central pivot 31 above pivots 28. The rod extends inwardly through wind box 16 and the inner end of the rod is joined to the expandable bellows thermostat 32. Thermostat 32 in turn is pivoted to bracket 33 which is suitably secured to base 2 within the longitudinal passage 26 between the legs of the baffles.

Thermostat 32 is of the type that expands by heat and rod 30 is of such a length that when thermostat 32 is in a contracted position due to temperature conditions within the drier, damper 27 is open and air is drawn into the wind box 16 through opening 29 and flows through blower unit 15 and out of outlet pipe 17. The thermostat may be set to expand at a temperature of 160° F. or other suitable temperature.

When the temperature within the drier reaches 160° F. or other suitable temperature for which the thermostat may be set, thermostat 32 expands and damper 27 closes opening 29 of the wind box through rod 30 by the lengthening of the thermostat.

When damper 27 is open air flows into the wind box without first flowing through drum 5, thereby allowing the air flowing through the heating chamber to attain a greater degree of heat and, as it passes through the drum, to liberate this heat to the drum and the clothes therein.

The amount of heat absorbed by the air from the heating element or burner 21 and conveyed to the clothes is substantially increased, due to the retarded circulation through the heating chamber and drum, and the initial heating of the clothes and drum is accomplished in a minimum of time and with a minimum amount of heat.

In addition, due to the lower resistance to the flow of air to the blower unit 15, a higher velocity of air through blower unit 15 and outlet pipe 17 is obtained, and as the moisture laden air from drum 5 is highly diluted by the drier air introduced through the damper opening 29, the tendency for the moisture to condense and collect in the blower unit 15 and outlet pipe 17 is practically eliminated.

Also, due to the higher velocity and drier air condition in outlet pipe 17, the discharge from the outlet pipe, if made to the outdoor atmosphere in freezing weather, will have much less tendency to form frost at the exhaust end of the outlet pipe.

As the unit continues in operation the temperature in the drum due to the heating of the metal and clothes gradually builds up to the 160° F. or other temperature at which the thermostat is set. This results in expansion of the thermostat, and damper 27 then closes, and the air circulates through the drier and is discharged through outlet 17 without any air flowing in through the damper.

The damper of the invention may be employed with any inlet conduit leading into the air stream which is flowing from drum 5 to blower unit 15. The conduit may be a wind box, as described, or the wind box may be eliminated and a pipe or conduit substituted which extends from the passage 26 to blower 15. The important requirement is that the damper be placed ahead of the blower unit in order that air may by-pass the drum and be sucked in through the damper opening and driven through the outlet pipe to maintain a continuous flow of air therethrough.

The damper 27 may also be pivoted so that the lower end pivots inwardly or outwardly to expose opening 29.

A further advantage of the invention lies in the cooling of the controls employed in the operation of the drier, and the outer casing. Controls, not shown, may be located in the housing 34 in the upper right front corner of the casing. Other controls for operation of the drier may be located between baffles 18 and 19 on the base of the drier or may be located in other positions in the unit between the baffles and the outer casing.

It has been found that both the controls in housing 34, the panels of casing 1 and motor 11 are cooled considerably when damper 27 is closed and air is flowing through the openings 23 on the right side of the drier viewed from the front in Figure 1 and over the outside of baffles 18 and 19, through openings 23' into the burner chamber.

In operation the damper thermostat 32 is set so that air is flowing through the damper opening substantially at all times during the drying cycle. This provides the cooling effect on the panels, controls and motor, described.

By providing for some flow of air through the damper opening for substantially the entire drying cycle air flowing from the drying drum 5 for discharge is diluted before it enters the blower which reduces the moisture content of the air discharged from pipe 17.

By locating the damper in conjunction with a separate opening in the inlet conduit or wind box the flow of air through the conduit and outlet pipe is not restricted and moisture does not accumulate within the drier.

The invention provides for initial heating of the clothes in drum 5 in an accelerated rate of time and at the same time eliminates the problem of moisture collecting in the outlet pipe by providing for unrestricted flow of air through the blower and outlet pipe.

The invention also minimizes the tendency for frost to form at the exhaust end of outlet pipe 17, when the pipe is exposed to freezing, due to the lower per cent of moisture in the discharged air and the higher velocity upon discharge.

Various embodiments of the invention may be employed within the scope of the accompanying claims.

I claim:

1. In a clothes drier, a rotary drier drum, a suction fan disposed to draw air therethrough to dry clothes confined therein, a heater for air passing into the drum, a double-walled casing for said drum having inlet ports for the entrance of air to the space between the walls of the casing and an opening from said space to said heater to supply a part of the air to said heater and drum, a damper disposed in the wall of said casing between said space and the entrance to the suction fan to bypass air which otherwise would pass through the heater and drum, and a thermostatic control for said damper responsive to the temperature of the air passing through the drum to control the bypass of air and maintain a predetermined temperature for the drying air in the drum.

2. In a clothes drier, a rotary drier drum, a suction fan disposed to draw air therethrough to dry clothes confined therein, a heater for air passing into the drum, a double-walled casing for said drum having inlet ports for the entrance of air to the space between the walls of the casing and an opening from said space to said heater to supply a part of the air to said heater and drum, a damper disposed in the wall of said casing between said space and the entrance to the suction fan to bypass air which otherwise would pass through the heater and drum, and a thermostatic control for said damper responsive to the temperature of the air passing through the drum to control the bypass of air and maintain a predetermined temperature for the drying air in the drum, said thermostat control being set relative to the damper opening to provide for a substantially reduced flow of air through the heater and drum during initial drier operations and for a more rapid flow of heated air through the drum after the latter and the clothes therein have become heated, thereby providing a rapid initial heating of the drum and for maximum dilution of the discharged air at a time when it is most saturated with moisture.

3. In a clothes drier, a rotary drier drum, a suction fan disposed to draw air therethrough to dry clothes confined therein, a heater for air passing into the drum, a damper disposed below said drum to admit air to said suction fan from the outside, a passage disposed to admit air to

said suction fan from the drier drum, and a thermostat disposed in said passage to be responsive to the temperature of the air passing to the suction fan from the drum and directly connected to said damper to move the same to an increased opening when the air temperature is low and toward closed position when the air temperature is high.

4. In a clothes drier, a rotary drier drum, a suction fan disposed to draw air therethrough to dry clothes confined therein, an outer casing for the drier, a baffle surrounding the drum and having diametrically opposed passages therethrough for air entering and discharging from the drum, a heater disposed to heat the air entering through the inlet passage in said baffle, a chamber for said heater connected by an opening to receive air from the space between the casing and baffle at one side of the drier, a port opening to admit air to the casing at the side opposite said last named opening, a passage from the discharge opening in said baffle to the intake of the suction fan, and a damper disposed to admit air from the space between said casing and baffle directly to said suction fan to thereby bypass air from said heater and drum during initial heating of the drum.

5. In a clothes drier, a rotary drier drum, a suction fan disposed to draw air therethrough to dry clothes confined therein, an outer casing for the drier, a baffle surrounding the drum and having diametrically opposed passages therethrough for air entering and discharging from the drum, a heater disposed to heat the air entering through the inlet passage in said baffle, a chamber for said heater connected by an opening to receive air from the space between the casing and baffle at one side of the drier, a port opening to admit air to the casing at the side opposite said last named opening, a passage from the discharge opening in said baffle to the intake of the suction fan, a damper disposed to admit air from the space between said casing and baffle directly to said suction fan to thereby bypass air from said heater and drum during initial heating of the drum, and a thermostat disposed in said last named passage and connected to said damper to control the latter in response to the varying temperature of air passing through the drum.

6. In a clothes drier, a rotary drier drum, a suction fan disposed to draw air therethrough to dry clothes confined therein, an outer casing for the drier, a baffle surrounding the drum and having diametrically opposed passages therethrough for air entering and discharging from the drum, a heater disposed to heat the air entering through the inlet passage in said baffle, a chamber for said heater connected by an opening to receive air from the space between the casing and baffle at one side of the drier, a port opening to admit air to the casing at the side opposite said last named opening, a passage from the discharge opening in said baffle to the intake of the suction fan, a damper disposed to admit air from the space between said casing and baffle directly to said suction fan to thereby bypass air from said heater and drum during initial heating of the drum, and a motor connected to drive said drum and said suction fan and disposed in the cold air stream between said casing and baffle to be cooled thereby.

7. In a drier having a drying chamber with an inlet and outlet, a heater disposed to heat air

passing into said chamber, a suction fan disposed to draw air through said chamber, a damper disposed to admit outside air to said suction fan to thereby control the passage of air through the heater and chamber, and a thermostat control for said damper directly connected thereto to move the damper toward closed position upon an increase in temperature of the air discharging from said chamber and toward open position upon a decrease in such temperature.
